UNITED STATES PATENT OFFICE.

WILLBERT R. DE HARPPORTE, OF MINNEAPOLIS, MINNESOTA.

HOT-WATER HEATER.

No. 872,612.

Specification of Letters Patent.

Patented Dec. 3, 1907.

Application filed June 10, 1907. Serial No. 378,151.

To all whom it may concern:

Be it known that I, WILLBERT R. DE HARPPORTE, a citizen of the United States, residing at Minneapolis, in the county of 5 Hennepin and State of Minnesota, have invented certain new and useful Improvements in Hot-Water Heaters; and I do hereby declare the following to be a full, clear, and exact description of the invention, such 10 as will enable others skilled in the art to which it appertains to make and use the same.

My invention has for its especial object to provide an improved boiler or hot water 15 heater for use in connection with hot water or steam heating plants, and to this end, it consists of the novel devices and combinations of devices hereinafter described and defined in the claims.

20 The improved boiler is illustrated in the accompanying drawings, wherein like characters indicate like parts throughout the several views.

Referring to the drawings, Figure 1 is a 25 view in side elevation, with some parts broken away, showing the improved boiler; and Fig. 2 is a view of the improved boiler taken on the line $x^2 x^2$ of Fig. 1.

The outer shell 1 of the boiler is shown as 30 rectangular in horizontal cross section, and is provided with the usual ash pit 2, pit door 3, grate 4 and fuel door 5. The upper portion of this shell 1 is bulged or laterally expanded at opposite sides of the boiler, and 35 the top thereof is curved to form an arch, as indicated at 1^a .

The fire box is formed by an inner metal shell 6 that extends parallel to the front, rear and side walls of the outer shell 1, but 40 is spaced apart therefrom to form a thin water chamber 7. By reference to Fig. 2, it will be seen that the upper portion of the inner shell 6 is bulged at its sides and has an arched top, and that at its lower portion it 45 is connected to the outer shell 1 above the grate 4, so that the water chamber 7 terminates above the grate, but it will, of course, be understood that the said inner shell, and consequently the water chamber, 50 might be extended below the grate, if desired.

Extending across the top of the combustion chamber of the boiler, but spaced below the arched top of the inner shell 6, is an 55 arched water leg 8. At its front and rear

ends this water leg 8 opens into the front and rear portions of the water chamber 7 and connects directly with the front and rear plates of the said inner shell 6. Arched deflecting plates 9, secured to the front and rear plates of the outer shell 1, project into the ends of the water leg 8, so that the heated water which rises in the front and rear end portions of the chamber 7 is caused to circulate within said arched leg 8. 65

The smoke pipe 10 is passed through the arched top of the outer shell 1 and registers with an opening in the arched top of the inner shell 6. It will also be seen that the products of combustion from the fire box can 70 pass upward in two directions through a wide but shallow draft passage 11 formed between the bulged portion of the inner shell 6 and the parallel walls of the arched leg 8, on their way to the smoke pipe 10. 75 A hot water outlet 12, as shown, opens through the arched top of the outer shell 1 from the uppermost portion of the water chamber 7, and a cold water return pipe 13 opens through the outer shell 1 into the lower 80 portion of said chamber 7.

The numeral 14 indicates a drain cock which, as shown, opens through the shell 1 from the lower portion of the water chamber 7. 85

As is evident, the bulged or laterally expanded portion of the shell gives a greater amount of radiating surface to the boiler and causes the flames to take a winding course around the water leg 8 and into the bulged 90 portion of said boiler, thereby increasing the efficiency of the boiler.

The above described arrangement not only affords a boiler which is of simple construction and capable of being made entirely from boiler iron or steel plate, but gives a boiler or heater a very high efficiency. 95

What I claim is:—

In a boiler or hot water heater, the combination with an outer shell 1 bulged and arched at 1^a , of an inner shell 6 spaced apart from said shell 1 to form a water chamber 7, the upper portion of said inner shell being bulged and arched and extended approximately parallel to the upper portion of said outer shell, a smoke pipe leading upward from an opening in the arched top of said inner shell, an arched water leg 8 located in the upper portion of the combustion chamber and spaced apart from the upper 110

portion of said inner shell to form a divided draft passage leading to said smoke pipe, curved deflecting plates 9 secured to said outer shell 1 and extending into the ends of 5 said water leg 8, and extending approximately parallel to the arch of said water leg substantially as described.

In testimony whereof I affix my signature in presence of two witnesses.

WILLBERT R. DE HARPPORTE.
